UNITED STATES PATENT OFFICE.

WILLIAM S. GRAHAM AND JAMES L. HIPPLE, OF CANTON, ILLINOIS, ASSIGNEES, BY
MESNE ASSIGNMENTS, TO FRED GERLACH AND ARNOLD B. KELLER, TRUSTEES,
BOTH OF CHICAGO, ILLINOIS.

MULTIPLE-GANG POWER-LIFT PLOW.

Application filed January 7, 1921. Serial No. 435,598.

To all whom it may concern:

Be it known that we, WILLIAM S. GRAHAM and JAMES L. HIPPLE, citizens of the United States, and residents, respectively, of Canton, in the county of Fulton and State of Illinois, and of Canton, in the county of Fulton and State of Illinois, have invented certain new and useful Improvements in Multiple-Gang Power-Lift Plows, of which the following is a full, clear, and exact specification.

Our invention consists of an improvement in multiple gang plows and our objects are to embody in a plow of this type a single traction actuated power lift mechanism for simultaneous control of the several gangs and to relate the gangs to each other and to the lift and draft devices so as to secure uniform depth of plowing by all the gangs as well as ample clearance when the gangs are elevated.

Another object is to connect the gangs so that when they are being lowered, the forward plow of a rear gang will lower faster than the last plow of the gang ahead, thus giving the plows comprising the rear gang the downward tilt necessary to run them into the ground point first.

A further object of our invention is to produce a plow of this type that can be turned in a comparatively short radius while preserving relative rigidity as to horizontal movement between the several sections or gangs.

Our invention accomplishes these objects by connecting the sections or gangs so that the rear end of one section is supported on the front of the next and so that they can flex and tilt on each other in a vertical plane but are held against motion in a horizontal plane, and by arranging the cranked axles and supporting wheels, and more particularly the intermediate supporting wheels, in such relation to the gangs and the lift device as to cause the plows on a rear gang to take the ground at the same time and with the same downward tilt as those on the front gang. In order to facilitate traveling, we support the rear gang on swiveled wheels in a novel manner which maintains the swiv-

eled spindles in vertical position in both lifted and lowered positions of the gangs.

With these and other objects in view, our invention consists of the organization and details of construction, or their equivalents, 55 herein described and defined in the claims.

Referring to the drawings—

Fig. 1 is a plan view of a multiple gang plow embodying our invention.

Fig. 2 is a side elevation showing the 60 gangs lowered.

Fig. 3 is an enlarged view of the central portion of the plow as seen in Fig. 2.

Fig. 4 is a similar view taken from the opposite side.

Fig. 5 is an enlarged plan view showing the rear gang and its connections to the front gang.

In the present instance our invention is disclosed in connection with a machine comprising two flexibly connected sections A and B, each of which may consist of four rigidly connected plows, the individual plows and the two sections being positioned relatively to each other in the usual stepped or echelon arrangement. A yoke member 10 is properly braced and secured to the front plow gang and the gang is supported on opposite cranked axles 11, 12, which are journaled on the gang and carry the land 80 and furrow wheels 13 and 14 respectively. The cranks 11^a, 12^a on the axles 11, 12, are oppositely inclined with respect to the direction of travel of the gang, that is, the forward axle 11 carrying the front furrow 85 wheel has its crank 11^a inclined towards the rear of the gang, while the axle 12 carrying the land wheel has its crank inclined toward the front. The means for turning the axles 11 and 12 for raising and lowering the gang 90 is that disclosed in United States patent to W. S. Graham #1,237,505 issued August 21, 1917, but other power lift devices could be substituted in our present invention. In general, this power lift consists of a clutch 95 member 15 journaled on a stub-shaft 16 projecting from and secured to the gang, said clutch member having sprocket teeth on its periphery and being connected by means of a sprocket chain 17 with the sprocket 18 100

fixed on the hub of the wheel 13. A supplemental clutch member 19 is also carried on shaft 16 and supports pawl mechanism adapted to engage internal teeth on member 5 15 and controlled by a trip 20 which is normally seated in one of opposite notches 19^a in the clutch member 19. Clutch member 19 is connected to the front axle 11 by a link 21 which is pivoted on the clutch member 10 and on a sector 22 which is sleeved on axle 11. A lever 23 is secured to axle 11 and carries the usual latch by which it may be locked in adjusted position on sector 22, this lever serving to adjust the position of the 15 front furrow wheel 14. A second sector 24 formed on the same sleeve as carries sector 22 has a lever 25 pivoted thereon and the end 25^a of this lever is connected by a link 26 to the crank 12^a on axle 12, this lever 20 serving to adjust the land wheel and the whole mechanism just described acting to turn the axles 11, 12, simultaneously in opposite directions to raise and lower the gang, all as set forth in more detailed manner in 25 the prior patent above referred to.

A transverse hitch bar 27 is secured to the front of the forward gang, as by hinged brackets 27^a, and extends laterally to a point beyond the land wheel 13. It carries converging draft links 28 for connection to a tractor, and its outer end is connected to the 30 rear gang in the manner to be described.

The rear gang is secured to forwardly extending members 29, corresponding to the 35 yoke member 10 of the front gang, and attached to the plows in the same manner, but preferably having the front ends connected and braced by the U-shaped member 30. At the front ends the members 29 have 40 vertical plates 31 fixed thereto and these are apertured to receive a transverse coupling rod 32 retained in the outer plate 31 by cotter pins 33 or equivalent means. The inner end of the coupling rod 32 extends 45 laterally towards the rear plow of the front gang to which is secured a vertical plate 34 with an offset rear portion 34^a which has an opening 35, preferably a vertical slot, in which the inner end of the coupling rod 32 is received and retained by means such 50 as a washer and cotter pin 36. The outer one of the plates 31 extends slightly beyond the member 29 and pivotally receives the bent end of the oblique brace rod 37 which 55 has its front end oppositely bent and pivoted in a plate or bracket 38 fixed to the front gang near the land wheel axle. A substantially triangular hitch plate 39 is fixed to, and depends from, the front end of 60 the outer member 29 and is provided with a vertical series of apertures to adjustably receive the rear end of a draft rod 40 which has its front end connected to the outer end of the hitch bar 27 in the manner

shown on the drawings, and which is preferably provided with a turn-buckle connection 40^a for purposes of adjustment. 65

With the construction described, the rear end of the front gang is supported on coupling bar 32 and the relation of the coupling bar 32 and the other connections above described to the gangs constitutes a coupling which allows the gangs to flex in a vertical plane about the bar 32 as an axis and the play of the end of bar 32 in the slot 35 70 permits sufficient independent vertical movement of the forward end of the rear gang to cause its plows to dip into the ground point first when the gangs are lowered, while the relation of rod 32 and brace 80 37 to the gangs prevents any relative movement between them in a horizontal plane. 75

The forward end of the rear gang is supported on opposite cranked axles 41, 42, corresponding to the axles 11, 12, of the 85 front gang, but the cranks 41^a, 42^a, are both inclined towards the forward end of the gang, instead of oppositely as in the case of the front gang and the relative positions of the land and furrow wheel axles 90 on the rear gang are reversed with respect to the front gang, the land wheel axle on the rear gang being in advance of the furrow wheel axle. The horizontal ends of the cranks 41^a, 42^a, are journaled in spindle 95 brackets 43 formed with vertical bearings 43^a in which are swiveled the upright spindles of the land and furrow wheels 44 and 45. The brackets 43 are also provided with upwardly directed arms 43^b to which are 100 pivoted rods 46 which extend parallel to the axle cranks and which are pivoted on the gang above the axle and serve to maintain the spindle bearings 43^a in vertical position whether the gangs are raised or lowered, the rod 46 for the land wheel being received in the upper portion of the hitch plate 39 while the rod for the furrow wheel is received in the upper part of a vertical plate 47 secured to the beam of the forward plow of the gang and through which the axle 42 passes. This plate has its rear edge bent outwardly at right angles at 47^a and the bent end receives a threaded bolt 48 which is positioned to be engaged by an arm 49 fixed on the crank of axle 42, the bolt forming an adjustable stop which limits the upward swing of crank 42^a. Arm 49 carries a laterally extending swiveled eye 50 at its end which slidably receives the end of a link 51 on which there is threaded a nut 51^a. The other end of link 51 is pivoted to the end of an upwardly extending crank arm 52 on the inner end of axle 41. The arm 52 also receives the rear end of a 120 connecting rod 53 which has its forward end pivoted to an upwardly extending arm 54 fixed to axle 12 on the front gang, the 125

rear end of rod 53 being bent laterally and passed through arm 52 to serve as a pivot pin for link 51, in the manner shown on the drawings (Fig. 5). Connecting rod 53 is preferably formed in sections connected by a turnbuckle 53^a for purposes of adjustment. A rear furrow wheel 55 with an upwardly extending spindle journaled in a bracket 56 supports the rear end of the 10 gang. The bracket 56 is mounted on a horizontal pivot at 57 and is connected to an upwardly extending lever arm 58 which is connected by the flexible link 59 to a vertical arm 60 fixed on axle 41, thus causing the bracket 56 to swing on its pivot to raise and lower the rear furrow wheel when the gangs are raised and lowered as heretofore done with single gangs.

With the construction above described, each actuation of the lift mechanism causes approximately a half revolution of the clutch member 19, which, through the links 21 and 26 operates to turn the cranked axles 11, 12, in opposite directions, resulting in corresponding shifting of the wheels and lifting or lowering of the front gang. At the same time the arm 54 on axle 12 and the connecting rod 53 transmit movement in a direct line to axles 41, 42, which are both rotated in the same direction owing to their connection through link 51, and the rear section of the plow is therefore raised or lowered in unison with the front.

It should be noted that owing to the slideable or lost motion connection of link 51 in the eye 50, the axle 42 is practically released from its connection to axle 41 when the gang has been lowered, as the stop-nut 51^a is then moved rearwardly out of contact with eye 50 on arm 49, as best seen on Figs. 3 and 4 and the intermediate furrow wheel 45 has its limit of elevation fixed by contact of arm 49 with stop 48 and is therefore independent of its lifting connection in that respect and functions as an adjustable gage wheel.

In consequence of the movement allowed the end of rod 32 in slot 35 the front of the rear gang dips before the rear plow of the 50 front gang does so. The effect of this is to cause the plows of the rear gang to run into the ground point first, thus eliminating interference to descent of the plows by stubble and trash, as would otherwise occur and insuring that the plows in each gang will reach plowing depth at practically the same instant, wheel 45 serving to determine the depth for both the rear of the front gang and the front of the rear gang. 55 When the link 51 moves forwardly during raising of the gangs, the nut 51^a is brought into contact with eye 50 and the axle 42 is swung in unison with axle 41.

Owing to the fact that the rear land wheel

44 and intermediate and rear furrow wheels 65 45, 55, are swivelly mounted, the raised gangs may be easily turned and transported although the sections are rigidly held against pivotal movement in a horizontal direction. 70

The present description exemplifies one form of our invention and the construction shown is subject to such changes as come within the scope of the following claims:

1. In a soil working machine, the combination of a plurality of flexibly connected sections, a vertically shiftable land and furrow wheel on the forward portion of each section, and a power lift device on one of the sections having operating connections with the wheels on each section. 75

2. In a soil working machine, the combination of front and rear sections, a vertically shiftable land and furrow wheel on the forward portion of each section, and a power lift device driven from the supporting wheel on one of the sections and connected to the wheels on the other section to shift all of said wheels. 85

3. In a soil working machine, the combination of front and rear flexibly connected sections, a vertically land and furrow wheel on the forward portion of each section, and a power lift device driven from the supporting wheel on the front 90 section and connected to the wheels on the rear section for shifting said wheels in unison. 95

4. In a soil working machine, the combination of front and rear sections, cranked 100 axles journaled on each section, supporting wheels on the cranks, a power lift device driven from one of the wheels and connected to the axles on one section for swinging the cranks, and means connecting the 105 axles on both sections for joint movement.

5. In a soil working machine, the combination of front and rear hingedly connected sections, a pair of opposite crank axles journaled on each section, means connecting the axles of each pair for joint rotation, supporting wheels on the cranks, a power lift device driven from one of the supporting wheels on the front section and connected to the front pair of axles, an arm 110 on one of the rear axles, and a link pivoted to an arm on one of the front axles and to the arm on the rear axle. 115

6. In a plow, the combination of a front plow gang, a rear plow gang positioned 120 laterally of and hinged to the front gang for movement in a vertical plane, opposite cranked axles journaled on each gang, wheels on the cranks of the front gang, brackets on the cranks of the rear gang, 125 wheels swiveled in said brackets, and means on one of the gangs for rotating all the axles in unison to lift and lower the gangs.

7. In a plow, the combination of front and rear connected plow gangs, opposite cranked axles journaled on each gang, supporting wheels on the cranks, and lifting means on the front gang connected to the axles of both gangs for rotating them in unison to raise and lower the gangs including a lost motion connection between the axles on the rear gang. 65
- 5 8. In a plow, the combination of front and rear offset plow gangs, opposite cranked axles journaled on each gang, a land and furrow wheel on the respective cranks of each gang the land wheel axle on the rear gang being in advance of the axle carrying the furrow wheel, and lifting means on the front gang connected to the axles of both gangs for rotating them in unison to raise and lower the gangs, including a lost motion connection between the axles of the rear gang. 70
- 10 9. In a multiple gang plow, a section comprising a gang of plows, a pair of opposite cranked axles journaled on the gang, brackets journaled on the cranks, supporting wheels swiveled in the respective brackets, links pivotally connecting the brackets to a fixed part of the gang, and lifting means connected to the axles for rotating them in unison. 75
- 15 10. In a multiple gang plow, a section comprising a gang of plows, a pair of opposite cranked axles journaled on the gang with the crank of the forward axle on the land side of the gang, brackets journaled on the cranks, land and furrow wheels swiveled in the respective brackets, links pivotally connecting the brackets to a fixed part of the gang, lifting means connected to the front axle for rotating it, and means connecting the two axles for rotation in the same direction including a lost motion connection. 80
- 20 11. In a plow, the combination of a front plow gang, a rear plow gang hinged to the front gang for movement in a vertical plane, a pair of opposite cranked axles journaled on each gang, land and furrow wheels on the respective cranks of each gang, the positions of the axles on one gang being reversed with respect to the other gang, and lifting means on the front gang connected to all the axles for rotating them in unison to raise and lower the gangs. 85
- 25 12. In a plow, the combination of a wheel supported front plow gang, a rear plow gang hinged to the front gang for movement in a vertical plane, a pair of opposite cranked axles journaled on each gang, land and furrow wheels on the respective cranks of each gang, the positions of the axles on one gang being reversed with respect to the other gang and the cranks of the rear gang both being directed toward the same end of the gang, and lifting means on the front gang connected to all the axles for rotating them in unison to raise and lower the gangs including means for rotating the axles of the front gang in opposite directions and those of the rear gang in the same direction. 90
- 30 13. In a multiple gang plow, the combination of front and rear plow gangs, means connecting the gangs for relative movement in a vertical plane, vertically shiftable supporting wheels on each gang, lifting means on one of the gangs having wheel shifting connections with the wheels on both gangs, and means operative during lowering of the gangs for causing the forward end of the rear gang to descend before the rear end of the front gang. 95
- 35 14. In a multiple gang plow, the combination of front and rear plow gangs, vertically shiftable land and furrow wheels on the forward portion of each gang, coupling means supporting the rear of the front gang on the front of the rear gang including means permitting vertical movement between the gangs, and lifting means on one of the gangs having wheel shifting connections with the wheels on both gangs. 100
- 40 15. In a multiple gang plow, the combination of front and rear plow gangs, vertically shiftable land and furrow wheels on the forward portion of each gang, coupling means supporting the rear of the front gang on the front of the rear gang including means permitting vertical movement between the gangs, lifting means on one of the gangs having wheel shifting connections with the wheels on both gangs, and means independent of the shifting connection for the furrow wheel on the rear gang for fixing the limit of its upward movement. 105
- 45 16. In a multiple gang plow, the combination of front and rear offset sections, vertically shiftable land and furrow wheels on the forward portion of each section, coupling means supporting the rear of the front section on the front of the rear section, including means permitting relative movement between them in a vertical plane, and an oblique brace member extending from the side of the front section to the front of the rear section and fixing them against movement horizontally. 110
- 50 17. In a multiple gang plow, the combination of front and rear gangs of rigidly connected plows, a transverse coupling bar on the rear gangs with its inner end loosely pivoted on the inner end of the rear gang, vertically shiftable supporting wheels on each gang, and unitary mechanism on the forward gang for shifting all the wheels to raise and lower the gangs in unison. 115
- 55 18. In a multiple gang plow, the combination of front and rear gangs of rigidly connected plows, a transverse coupling bar on the rear gangs with its inner end loosely pivoted on the inner end of the rear gang, vertically shiftable supporting wheels on each gang, and unitary mechanism on the forward gang for shifting all the wheels to raise and lower the gangs in unison. 120
- 60 19. In a multiple gang plow, the combination of front and rear gangs of rigidly connected plows, a transverse coupling bar on the rear gangs with its inner end loosely pivoted on the inner end of the rear gang, vertically shiftable supporting wheels on each gang, and unitary mechanism on the forward gang for shifting all the wheels to raise and lower the gangs in unison. 125

connected plows, a transverse coupling bar on the rear gang with its inner end loosely pivoted on the rear end of the forward gang, vertically shiftable supporting wheel on each gang, unitary mechanism on the forward gang for shifting all the wheels to raise and lower the gangs in unison, and a pivoted brace member extending from the side of the front gang and connected to the outer end of said coupling bar for fixing 10 the gangs against relative movement horizontally.

In testimony whereof we affix our signatures.

WILLIAM S. GRAHAM.
JAMES L. HIPPLE.
